UNITED STATES PATENT OFFICE.

HAROLD FLATER, OF NORRKÖPING, SWEDEN.

PITMAN CONNECTION FOR MOWERS.

1,241,504.

Specification of Letters Patent.

Patented Oct. 2, 1917.

Application filed June 29, 1917. Serial No. 177,760.

To all whom it may concern:

Be it known that I, HAROLD FLATER, a citizen of the United States, residing at Norrköping, in the county of Östergötland 5 and State of Sweden, have invented certain new and useful Improvements in Pitman Connections for Mowers, of which the following is a full, clear, and exact specification.

10 My invention relates to pitman connections for mowers.

The object of the invention is to provide means whereby the wear between the pitman and its coöperating parts is automatically compensated for and the parts at all 15 times are held in the proper adjustment.

In the accompanying drawings I have for the purpose of illustration shown one embodiment of my invention, and in these 20 drawings—

Figure 1 is a side elevation of the pitman connection; and

Fig. 2 is a section taken on line 2—2 of Fig. 1, looking in the direction of the arrows.

The stubbleward end 10 of the body portion of the pitman, which is preferably made of wood, is provided with resilient straps 11, 12, and these straps are provided at their 30 ends with inwardly extending conical bearing heads 13, 14. The resilient straps 11, 12 are connected by means of a clamping bolt 15, which is threaded into the strap 11 and extends loosely through the strap 12. This 35 bolt 15 is provided with a head 16 which bears against the strap 12 when the bolt is in clamping position. The strap 12 is also provided with a tension spring 17 formed of a flat resilient strap, and this spring is 40 clamped or riveted to the strap by means of rivets 18, and when under tension tends to move toward strap 12. The spring is bifurcated at its stubbleward end, forming a fork 19 which receives the clamping bolt 45 15, and this bolt is grooved as shown at 20 to receive the forked end of the spring.

In the form illustrated in the drawings, the conical heads 13, 14 of the resilient straps are received in similarly shaped recesses or sockets formed in the bearing box 21, which is carried by the crank pin of the mower. In adjusting my pitman to the bearing box, the clamping bolt 15 is turned, thereby drawing the resilient straps toward 55 each other and drawing the heads 13, 14 into the sockets of the bearing member 21.

This bolt is initially adjusted so that the straps and bearing heads are in proper adjustment with relation to the bearing box. After the machine has been run for a considerable period under normal conditions, the wear between the bearing heads 13, 14 and the bearing box will be sufficient to permit considerable lost motion, and as a consequence the machine will not operate efficiently. However, by the use of the flat spring 17 above described, this wear is taken up and the tension of the spring will cause the pitman strap 11 to be drawn toward the pitman strap 12, thereby taking up the wear 70 and maintaining the parts in proper adjustment.

While I have in this application specifically described one embodiment which my invention may assume in practice, it is, of course, to be understood that the invention is not limited to the specific form shown herein, but may be modified without departing from the spirit of the invention.

What I claim as new and desire to secure 80 by Letters Patent of the United States is:

1. In a pitman connection, a pitman having resilient straps, and means located between said straps for forcing the straps toward each other and thereby compensating 85 for wear between the straps and the coöperating member.

2. In a pitman connection, a pitman having resilient straps, a clamping bolt for forcing said straps toward each other, and means coöperating with said bolt and fixedly secured to one of said straps for automatically adjusting said bolt and straps.

3. In a pitman connection, a pitman having resilient straps provided with conical bearing surfaces on the ends thereof, means for clamping said straps, and additional means located between said straps and coöperating with said clamping means for forcing said straps toward each other.

4. In a pitman connection, a pitman having resilient straps provided with conical bearing surfaces on the ends thereof, a bearing box having sockets for receiving said bearing surfaces, a clamping bolt loosely carried by one of said straps and threaded into the other of said straps, and means fixedly secured to one of said straps and coöperating with said clamping bolt for forcing said straps and bearing surfaces into 105 said sockets.

5. In a pitman connection, a pitman hav-

ing resilient straps, clamping means for said straps, and a flat spring carried by one of said straps and located between said straps for forcing said straps toward each other.

5 6. In a pitman connection, a pitman having resilient straps, a clamping bolt for forcing said straps inwardly, said bolt having an annular groove therein, and a flat resilient spring fixedly carried by one of said 10 straps and having a forked end engaging said groove for actuating said bolt to force said straps toward each other.

7. In a pitman connection, a pair of straps, one of which is resilient, and means

located between said straps for forcing said 15 resilient strap toward the other strap.

8. In a pitman connection, a pair of straps, one of which is resilient, and means fixedly secured to one of said straps for forcing said resilient strap toward the other 20 strap.

9. In a pitman connection, a pair of straps, one of which is resilient, and means fixedly secured to said resilient strap for forcing said straps toward each other. 25

In testimony whereof I affix my signature.

HAROLD FLATER.
